Attorney

UNITED STATES PATENT OFFICE.

EDWARD H. ROY, OF LOUISVILLE, KENTUCKY.

REFRIGERATOR.

1,414,097.

Specification of Letters Patent. Patented Apr. 25, 1922.

Application filed February 13, 1922. Serial No. 536,074.

To all whom it may concern:

Be it known that EDWARD H. ROY, citizen of the United States, residing at Louisville, in the county of Jefferson and State of Kentucky, has invented certain new and useful Improvements in Refrigerators; of which the following is a specification.

This invention relates to refrigerators and has special reference to a combined refrigerator and show case.

One important object of the invention is to improve the general construction of devices of this character.

A second important object of the invention is to provide an improved combination of ice chest and cold storage show case wherein any ordinary type of cold storage show case may be used so that merchants already having such show cases will not find it necessary to discard the same.

A third important object of the invention is to provide an improved combination of this class wherein the ice chest is arranged to permit goods to be withdrawn therefrom directly on top of the show case so that the samples of the goods sold may be kept in the show case and actual sales made from the ice chest without making it necessary for the attendant to leave the show case or disturb the samples therein.

With the above and other object in view, the invention consists in general of certain novel details of construction and combinations of parts hereinafter fully described, illustrated in the accompanying drawings, and specifically claimed.

In the accompanying drawings, like characters of reference indicate like parts in the several views, and:—

40 Figure 1 is a perspective view of the improved combination refrigerator and show case, the view being taken from the rear of the show case and showing the side of the refrigerator next said show case with its main and delivery doors.

Figure 2 is a vertical section taken longitudinally through the center of the show case and cutting the ice chest or refrigerator in the same plane.

50 In the construction here shown, which is to be taken as generally typical of the invention, there is provided an ice chest or refrigerator having an outer casing consisting of inner and outer walls 10 and 11 between

which is a suitable heat insulating packing 12. This casing is provided in its top with filling hatches 13 and at one side of its front is a large door 14. At the other side of the front and immediately above the floor thereof is an opening 15 above which is a door 16. Within the casing and spaced from the walls thereof is an ice receiving chamber formed with inner and outer metallic walls 17 and 18. Secured to the top edges of the inner side walls 17 is a top 19 but the space 65 between the outer walls 18, which extend above said inner walls 17, is not covered in. There are no ice chamber walls in front so that this part of the storage space 20, which lies beneath the top 19 and 70 is surrounded on three sides by the ice chamber is open for access through the doors 14 and 16 and also communicates by means of the opening 15 with the show case. The ice chamber is provided with the usual drain 75 and overflow pipes indicated generally at 21.

The showcase is of the usual general form, being provided on its front top and one end with double walled glazing 22 and having a heat insulating bottom 23. The remaining 80 end of this show case is open and abuts against the refrigerator around the opening 15. On the back of the show case are the usual sliding doors 24. From the top of the showcase remote from the refrigerator leads a pipe 25 which is provided with a valve 26 and opens into the upper part 85 of the refrigerator at 27 so as to communicate with the space between the inner wall 10 of the casing and the outer wall 18 of 90 the ice chamber. Under these conditions with the valve 26 open, a current of air will be established from the cold bottom part of the refrigerator through the show case and back through the pipe 25 to the upper part 95 of said refrigerator. It will also be observed that the location of the door 16 is such that articles may be drawn from the refrigerator on to the glass top of the show case with a minimum of handling.

There has thus been provided a simple and efficient device of the kind described and for the purposes specified.

It is obvious that minor changes may be made in the form and construction of the invention without departing from the material principles thereof. It is not therefore desired to confine the invention to the exact form

herein shown and described, but it is wished to include all such as properly come within the scope claimed.

Having thus described the invention, what is claimed as new, is:—

1. The combination with a refrigerator having an outer casing and an inner storage chamber spaced from the side walls of the outer casing, said inner chamber comprising a removable casing, having spaced inner and outer walls to provide an ice receiving space; of a show case having one end open and abutting against the refrigerator, said refrigerator being open at its lower part to afford communication to the open end of the show case, and a pipe extending upward from the top of the show case at the end remote from the refrigerator and then extending horizontally to a point adjacent to the top of the refrigerator, said pipe being continued and opening into the space in the refrigerator between the ice chest and the side wall of the storage chamber adjacent to top of said refrigerator, said pipe being provided intermediate its ends with a cut off valve.
- 20 of the casing.

2. The combination with a refrigerator having an outer casing and an inner storage

chamber spaced from the side walls of the outer casing, said inner chamber comprising a removable casing having spaced inner and outer walls to provide an ice receiving space; of a show case having one end open and abutting against the refrigerator, said refrigerator being open at its lower part to afford communication to the open end of the show case, and a pipe extending upward from the top of the show case at the end remote from the refrigerator and then extending horizontally to a point adjacent to the top of the refrigerator, said pipe being continued and opening into the space in the refrigerator between the ice chest and the side wall of the storage chamber adjacent to top of said refrigerator, said pipe being provided intermediate its ends with a cut off valve.

In testimony whereof I affix my signature.

EDWARD H. ROY.
